UNITED STATES PATENT OFFICE.

HARRY MARCUS, OF MINNEAPOLIS, MINNESOTA.

LEGGING.

1,367,750.

Specification of Letters Patent.

Patented Feb. 8, 1921.

Application filed November 16, 1918. Serial No. 262,768.

To all whom it may concern:

Be it known that I, HARRY MARCUS, a citizen of the United States, residing at Minneapolis, in the county of Hennepin and State of Minnesota, have invented certain new and useful Improvements in Leggings; and I do hereby declare the following to be a full, clear, and exact description of the invention, such as will enable others skilled in the art to which it appertains to make and use the same.

My invention relates to improvements in leggings and has for its primary object to provide a legging that will keep its shape and snugly fit the wearer's leg, irrespective of the size or shape.

To the above end, the invention consists of the novel devices and combinations of devices hereinafter described and defined in the claim.

In the accompanying drawings, which illustrate the invention, like characters indicate like parts throughout the several views.

25 Referring to the drawings,

Figure 1 is an outside view showing the improved legging on a wearer's leg;

Fig. 2 is a view corresponding to Fig. 1, with the exception that it is an inside view;

Fig. 3 is a transverse section taken through the legging on the irregular line 3-3 of Fig. 1;

Fig. 4 is an inside view of the legging spread out flat;

Fig. 5 is a vertical section taken on the line 5-5 of Fig. 4; and

Fig. 6 is a detail view in transverse section taken on the line 6-6 of Fig. 4.

40 The legging comprises an inner member 7 and an outer member 8, said members being provided with linings 9 and 10, respectively. These two members, together with their linings, are cut from a piece of cloth or other fabric from patterns so designed, that when the longitudinal edges of said members and linings are joined together by stitching, the legging is given a shape that will snugly fit the wearer's leg and shoe.

50 In the drawings, the wearer's leg and shoe are indicated by the numerals 11 and 12, respectively. Between the inner legging member 7 and its lining 9, is placed a fabric padding 13, preferably felt. Closely posi-

tioned rows of stitches 14 extend over the entire surface of the legging member 7 and connect its lining 9 and padding 13 thereto. These rows of stitches 14 are arranged in a novel and fantastic arrangement, as shown in Fig. 4, to stiffen the inner member of the legging and also hold the same in the desired form, wherein it is transversely rolled, bulged at the center of the calf and ankle portions and contracted between these two points, as best shown in Fig. 5.

The outer legging member 8 and its lining 10 are longitudinally divided and the back portions thereof have sufficient width to afford a flap 15, which extends under the front portion of said outer legging member. Parallel reinforcing strips 16 and 17 are secured by stitches, the former to the front portion of the outer legging member 8, at the free longitudinal edge thereof, and the latter thereof is secured to the rear portion of said outer legging member, at the junction of the flap 15 therewith.

By reference to Fig. 1, it will be noted that the reinforcing strips 16 and 17 extend the full length of the legging and the lower end of the strip 17 is extended to form a loop 18, which passes under the shoe 12, just forward of the heel, and is secured by stitches to the bottom of the inner legging member 7, as shown in Fig. 85 2. The loop 18 is provided with a lining 19, which reinforces the same and also gives said loop a neat and finished appearance.

Longitudinally spaced hooks 20 are secured to the strip 16 and longitudinally spaced eyelets 21 are secured to the strip 17. Both the hooks 20 and eyelets 21 extend completely through the respective strips, legging and its lining and are clenched on their inner ends in the customary manner to secure the same in position. A cord 22 is interlaced with the hooks 20 and eyes 21 to connect the free longitudinal edges of the legging member 8.

100 By reference to Figs. 1 and 2, it will be noted that the outer and inner sides of the legging are dipped considerably, where the loop 18 is attached thereto, and the front and rear lower end portions of the legging are 105 cut relatively high to permit free ankle movement, and thus avoid wrinkling or creasing of the legging.

The above described legging has, in actual usage, proven highly efficient for the purpose had in view.

What I claim is:—

- 5 A legging having substantially its entire inner face stitched in rows, certain of which extend substantially parallel to the outer edges of said inner face, and certain other of said rows extend diagonally from the
10 top to the bottom of the legging and cross

at substantially the center thereof to curve the inner face of the legging both longitudinally and transversely.

In testimony whereof I affix my signature in presence of two witnesses.

HARRY MARCUS.
